DEVICE FOR BACK FILLING HOLES
Lattie M. Tillman, 1340 NW. 131st St., North Miami, Fla.
Filed Dec. 10, 1962, Ser. No. 243,447
6 Claims. (Cl. 294—69)

This device relates to an apron for back filling holes that have been drilled for pole, anchors and the like.

A principal object of the present invention is to provide an apron for receiving and collecting earth deposited thereon by a drill and the like that is digging the hole and thereby protecting the surrounding area from becoming soiled by the earth.

Another object of the present invention is to provide an apron for back filling holes for poles, anchors, etc., which is simple in construction and in its use and readily effective to receive the earth placed thereon during the drilling of the hole and then replacing the earth back into the hole.

A further object of the present invention is to provide an apron for back filling pole and anchor bores which results in considerable savings in time and labor and permits the work to be done without despoiling the lawn and plants which are in the immediate area.

A still further object of the present invention is to provide an apron for back filling pole holes with a reusable panel permitting the back filling of the pole hole and the retention of the excess earth for dumping away from the pole.

With these and other objects in view, the invention will be best understood from a consideration of the following detailed description taken in connection with the accompanying drawings forming a part of this specification, with the understanding, however, that the invention is not confined to any strict conformity with the showing of the drawings but may be changed or modified so long as such changes or modifications mark no material departure from the salient features of the invention as expressed in the appended claims.

In the drawings:

FIGURES 1 and 2 are bottom and top plan views respectively of an apron for back filling holes constructed in accordance with my invention.

FIGURE 3 is a fragmentary sectional view taken along the line 3—3 of FIGURE 1.

FIGURE 4 is a cross sectional view of a hole being dug showing my apron in place to receive the earth.

FIGURE 5 is a similar view with a pole anchor placed in the hole.

FIGURE 6 is a similar view showing the manner of back filling the hole by use of my apron.

FIGURE 7 is a cross sectional view of my apron shown ready to back fill a pole hole.

FIGURE 8 is a similar view showing the pole hole after being back filled.

FIGURE 9 is a perspective view showing the apron ready to be removed from the pole and pole hole with earth which is excess.

Referring to the drawings wherein like numerals are used to designate similar parts throughout the several views, the numeral 10 refers to my apron consisting of a body portion 11 made of canvas, plastic and the like having a circular outer periphery 12 and an inner circular cut out portion 13. The body portion 11 must be made of a strong, tough though pliable material inasmuch as large quantities of dirt, stone, etc. will be contained and lifted in the air by the apron 10.

To support a quantity of earth, the apron 10 is provided with a plurality of straps 14 and 15 which extend radially of the body portion 11 and are symmetrically disposed about the circumference of the apron 10. The

2

straps 14, 15 are sewn or otherwise fastened to the body portion 11 and extend beyond the periphery 12 of the body portion 11 a distance substantially equal to the radius of the apron 11. The straps 14 and 15 form two identical groups terminating at rings 16 and 17 to which the respective straps are secured.

Further straps 18 secured to the apron 11 extend inwardly of the periphery 13 and have their ends fastened to a plurality of rings 19. There are eight such straps 18 positioned symmetrically about the inner periphery 13 of the apron 11 with each pair of straps 18 secured at their free ends to a ring 19 of which there are four. The rings 19 are engaged by snap hooks 20 that are fastened to lines 21 extending to a ring 22 that is secured to one end of an elongated strap 23. During the operation of the apron device 10 the other end of the strap 23 will be engaged by a quick release grip type buckle 24 which is secured to the periphery 12 of the apron 11 at mid-position between the two groups of straps 14 and 15.

At the opposite side of the apron 11, also between the two groups of straps 14 and 15, there is an opening 25 extending the full radius of the apron 11 forming panels 30 and 31. The edges of the apron 11 at the opening 25 are provided with snap hooks 26 and rings 27 for releasably securing the edges of the panels 30 and 31 together. A flap 28 which covers the opening 25 to prevent dirt, etc. from passing therethrough when such is not desired, is fastened along one edge of the panel 30 as at 29 and extends over the opening 25 to the other panel 31.

The apron device 10 is also provided with an anchor rod retaining strap 32 which has loops 33 and 34 at the ends thereof and is positioned radially of the apron 11 and fastened inwardly of member 34 to the inner and outer peripheries 13 and 12 of the apron 11. The function of the strap 32 is to engage an anchor rod when earth is being back filled into a hole to prevent movement thereof as explained in greater detail hereinafter.

40 In the normal use of my apron device 10, the apron as shown by FIGURE 2 is placed on the earth over the site a pole anchor hole is to be dug. However, since all of the dirt removed to drill the hole is to be back filled, the strap 23 is removed from its connection to the inner rings 19. The anchor hole 35 is drilled as illustrated by FIGURE 4 by a conventional drill 36 extending through the central opening 13 of the apron body portion 11. As the drill 36 rotates and bites into the earth, it deposits the earth on the apron 11. After the hole 35 has been dug to its desired depth, the drill 36 is removed and an anchor 37 placed therein with its anchor 38 extending upwardly and outwardly of the hole 35. Loop 33 of the strap 32 is placed over the end of the anchor rod 38 and the strap 32 is pulled taut to secure the anchor rod 38 against being dislodged. The two rings 16 and 17 are now brought together and engaged by a hook of a hoist or lift (not shown) and lifted upwardly. The apron 10 is raised above the ground as shown by FIGURE 6 with the central portion of the apron 11 extending downwardly permitting the earth to fall through the opening 13 to back fill the hole 35. All of the earth will fall directly into the hole 35 to fill same, the earth later being tamped and then sodded or returned to its original condition. The strap 32 will then slip off the end of the anchor rod 38.

65 To use my apron 10 for digging pole or post holes and back filling same, the apron 10 is again spread over the spot the pole hole is to be dug and the drill 36 used as explained above and shown by FIGURE 4. After the pole hole 39 has been dug and the drill removed, a pole 40 is placed through the opening 13 in the apron 11 and into the hole 39, supported therein by the conventional manner (not shown). As before, the two rings 16 and

17 are gathered together and engaged by a lift hook and line 41. The strap 23 is now taken in hand and the snap hooks 20 thereof are engaged to the central rings 19. The strap 23 is then slipped through the rings 16, 17, pulled tightly and then threaded through and engaged by the buckle 24 to secure the strap 23. Now, the hoist picks up and lifts the apron device 10 off the ground and shown by FIGURE 7. Very little if any earth will fall back into the opening 39 until the strap 23 is loosened at the buckle 24. The weight of the earth in the apron 11 will cause the inner portion of the apron 11 to slide downwardly as shown by FIGURE 8 to cause some of the earth to fall through the central opening 13. Only sufficient slack is provided the strap 23 to permit the pole hole 39 to become filled when tamped with the excess earth remaining in the apron 11. Snap hooks 26 are now disengaged from their respective rings 27 to separate the panels 30 and 31 and provide the radial opening 25. The apron device 10 containing the excess earth can now be swung away from the pole 40 by permitting the pole 40 which is at the central opening 13 to pass along the radial opening 25 to beyond the periphery 12 of the apron 11. The excess earth in the apron 11 can now be taken away from the site of the pole 40 and dumped whenever desired.

What I claim as new and desire to secure by Letters Patent of the United States is:

1. A device for back filling holes comprising a pliable body portion having a medially disposed opening and a further opening extending from said first named opening to an outer periphery of said body portion, releasable fastening means extending across said further opening for closing said opening, a plurality of elongated members secured to said body portion and extending beyond the periphery of said body portion, means connecting the free ends of said elongated members for lifting said pliable body portion at said outer periphery and further means connected to said body portion at said medially disposed opening for lifting said body portion at said inner portion of said pliable body portion.

2. A device for back filling holes comprising a substantially circular pliable body portion having a substantially concentrically disposed opening and a further opening extending from said first named opening to the outer periphery of said pliable body portion, releasable fastening means secured to said body portion at said further opening for closing said opening, a plurality of elongated members secured to said body portion and extending beyond the periphery of said body portion, means connecting the free ends of said elongated members for lifting said pliable body portion at said outer periphery and further means connected to said body portion at said concentrically disposed opening for lifting said body portion at said inner portion of said pliable body portion.

3. A device for back filling holes comprising a pliable body portion having a medially disposed opening and a further opening extending from said first named opening to an outer periphery of said body portion, releasable fastening means extending across said further opening for closing said opening, a plurality of elongated members secured to said body portion and extending beyond the periphery of said body portion, means connecting the free ends of said elongated members for lifting said pliable body portion at said outer periphery, fastening members secured to said pliable body portion about said medially disposed opening, a further fastening member engaging each of said first fastening members, extensible members

connected at one end to said further fastening members and joined together at their other ends and a releasable buckle secured to said pliable body portion at said outer periphery for securing said other ends of said extensible members.

4. A device for back filling holes comprising a substantially circular pliable body portion having a substantially concentrically disposed opening and a further opening extending from said first named opening to the outer periphery of said pliable body portion, releasable fastening means secured to said body portion at said further opening for closing said opening, a plurality of elongated members secured to said body portion and extending beyond the periphery of said body portion, means connecting the free ends of said elongated members for lifting said pliable body portion at said outer periphery, fastening members secured to said pliable body portion about said medially disposed opening, a further fastening member engaging each of said first fastening members, extensible members connected at one end to said further fastening members and joined together at their other ends and a releasable buckle secured to said pliable body portion at said outer periphery for securing said other ends of said extensible members.

5. A device for back filling holes comprising a substantially circular apron, having a concentrically disposed opening and an elongated aperture extending from said opening and the periphery of said circular apron, a plurality of releasable fastening members secured to said apron adjacent said aperture for closing said aperture, a flap secured along one edge to said apron and extending over said aperture, a plurality of radially disposed straps secured to said apron and extending beyond the periphery of said apron, said straps forming two groups, said aperture being disposed between said groups of straps, a ring secured to said straps of each of said groups for lifting said apron at the periphery thereof, and a plurality of ring members secured to said apron at said concentrically disposed opening for lifting said apron at the inner portion of said apron.

6. A device for back filling holes comprising a substantially circular apron, having a concentrically disposed opening and an elongated aperture extending from said opening and the periphery of said circular apron, a plurality of releasable fastening members secured to said apron adjacent said aperture for closing said aperture, a flap secured along one edge to said apron and extending over said aperture, a plurality of radially disposed straps secured to said apron and extending beyond the periphery of said apron, said straps forming two groups, said aperture being disposed between said groups of straps, a ring secured to said straps of each of said groups for lifting said apron at the periphery thereof, a plurality of ring members secured to said apron at said concentrically disposed opening, a releasable fastening member secured to each of said last named ring members, an extensible member secured to each of said last named releasable fastening members, strap means secured to said extensible members at their free ends and a buckle secured to said apron between said groups of straps and substantially opposite said aperture for receiving said strap means after having passed said strap means through said rings.
